[57] **CLAIM**

The ornamental design for an automatic teller machine cabinet, as shown and described.

DESCRIPTION

FIG. 1 is a perspective view of an automatic teller machine cabinet, according to my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a rear elevational view thereof.

The broken line showing of other elements of an automatic teller machine cabinet in FIGS. 1, 2 and 4 is for illustrative purposes only and forms no part of the claimed design.
